UNITED STATES PATENT OFFICE.

EUGÈNE ADOLPHE PIN, OF CLICHY, FRANCE.

GELATINOUS FILM AND PROCESS OF FORMING THE SAME.

1,184,772.

Specification of Letters Patent.

Patented May 30, 1916.

No Drawing.

Application filed January 20, 1916. Serial No. 73,128.

To all whom it may concern:

Be it known that I, EUGÈNE ADOLPHE PIN, engineer, resident of Clichy, Seine, post-office address 52 Rue du Reservoir, France, have invented new and useful 5 Gelatinous Films and Process of Forming the Same, which gelatinous films are fully set forth in the following specification.

This invention relates to a process by 10 which a film of gelatin, or other substance adapted to form a film when dried, can be formed on a support, for instance of paper, to which the film will adhere so as to enable it to be subjected to the manipulations required in photography; but from which it 15 can be nevertheless easily detached, so that the film thus separated from its support, can be used as a transparency.

In the following description the film will 20 be taken by way of example to be a photographic film, and the support, a sheet of paper; but the invention is not limited to a photographic film or a paper support.

Soap suds are obtained by preparing hot 25 (at the boiling temperature) an aqueous solution of any desired soap (soda lye and any oil), preferably a soap made from cocoanut oil, with or without the addition of foreign substances such as resins and waxes.

The soap is first dissolved in a little water, and after it is completely dissolved, such a 30 quantity of water is added that the final product contains one liter of water per 8 grams of soap. These proportions are not, 35 however, absolutely essential, and are given merely by way of example.

Paper of the desired size and strength is then taken, and the solution obtained as described is spread thereon preferably by 40 means of ordinary emulsioning apparatus. Then it is left to dry or it is dried. Then on the said paper the film is formed and soap is preferably incorporated with the film-forming substances.

The various operations can be advantageously carried out in the following manner:—1000 grams of gelatin are taken and soaked cold in 8000 grams of water. The product thus obtained is placed in a water bath to raise its temperature to about 80° C. As soon as the gelatin is dissolved, a solution is added to it of 20 grams of 6% chrome alum and 200 grams of water. The mixture thus obtained is maintained in a

liquid state; and at the expiration of about 55 half an hour, first a solution is stirred in of 166 grams of soap and 500 grams of water, and then 100 cubic centimeters of glycerin at 28° are added. This composition is then spread on the previously prepared paper, preferably by ordinary emulsioning apparatus.

The whole is dried or left to dry, and the said paper will be found to be covered with a film which adheres to it, but is nevertheless readily detachable. These various operations are completed by the spreading of a photographic sensitive layer, in the usual manner. Thus a photographic paper is obtained with a film, which, as proved by 70 experience, offers, from the point of view of adhesion to the paper, very special qualities. It can be subjected to any manipulations to which photographic proofs have to be subjected without risk of becoming accidentally detached.

Obviously the invention is not limited to the methods described, but comprises for instance using for a substratum, wood, glass or fabric instead of paper, as well as 80 employing for the film, acetate of cellulose, mucilage, collodion or varnish.

I claim:

1. A process of forming a gelatinous film on a temporary support, consisting in coating the support with an aqueous solution of soap and then depositing thereon a gelatinous substance.

2. A process of forming a gelatinous film on a temporary support, consisting in coating the support with an aqueous solution of soap, then depositing thereon a mixture of a gelatinous substance and an aqueous solution of soap.

3. A process of forming a gelatinous film on a temporary support, consisting in coating the support with an aqueous solution of soap, then depositing thereon a mixture of a gelatinous substance and an aqueous solution of soap and then spreading a photographic sensitive layer on the gelatinous film.

4. A process of forming a gelatinous film on a temporary paper support, consisting in coating the support with an aqueous solution of soap made from cocoanut oil, then depositing thereon a mixture of gelatin, glycerin and an aqueous solution of soap

made from cocoanut oil, and then spreading a photographic sensitive layer on the gelatinous film.

5. A process of forming a gelatinous film on a temporary support consisting in coating the support with an aqueous solution of soap mixed with resinous substances, then depositing thereon a mixture of a gelatinous substance and an aqueous solution of 10 soap.

6. A film on a temporary support, comprising a gelatinous substance deposited on the temporary support previously coated with an aqueous solution of soap.

15. 7. A film on a temporary support comprising a gelatinous substance with an addition of an aqueous solution of soap, deposited on the temporary support previously coated with an aqueous solution of 20 soap.

8. A photographic film on a temporary support, comprising a gelatinous substance with an addition of an aqueous solution of soap, deposited on the temporary support

previously coated with an aqueous solution 25 of soap, and a sensitive layer deposited on the gelatinous film.

9. A photographic film on a temporary support, comprising a mixture of gelatin and glycerin, with an addition of an aqueous 30 solution of soap made from cocoanut oil deposited on a temporary paper support previously coated with an aqueous solution of soap made from cocoanut oil, and a sensitive layer deposited on the gelatinous film.

35 10. A film on a temporary support, comprising a gelatinous substance with an addition of an aqueous solution of soap, deposited on a temporary support previously coated with an aqueous solution of soap, 40 with resinous substances incorporated.

In testimony whereof I have signed this specification in the presence of two subscribing witnesses.

EUGÈNE ADOLPHE PIN.
